RADIO RECEIVING APPARATUS

William Scott Stewart, Chicago, Ill.

Application November 5, 1927. Serial No. 231,189

5 Claims. (Cl. 250—40)

The present invention relates to a simplified form of tuning control for radio receiving apparatus that allows of practically instantaneous change from one frequency to another without 5 the necessity of carefully adjusting dials and other control devices associated with such apparatus; and which lends itself to ready operation by even such persons as are unfamiliar with radio instruments.

10 One of the objects of the present invention is to provide a number of complete, but independent, tuning units for the radio receiving set. These tuning units are capable of being thrown into and out of service by the mere throw of 15 a switch, and are independently adjustable so that any one of the said tuning units may be adjusted for a particular frequency.

It is the usual modern practice in radio receiving sets to control the frequency to which 20 the set will respond, or in other words the wavelength, by varying the inductance and capacity of the circuits associated with the amplifier and detector tubes or other electric wave detecting devices. This may be accomplished by a number 25 of different methods, as for example by varying the inductance, as by use of a variometer or by some device capable of changing the number of coils of a solenoid or similar coil, by varying the capacity bridged across such coil, as by the use 30 of a variable condenser; or by varying both the inductance and the capacity.

In the course of the development in the art 35 of constructing radio receiving apparatus, it has become standard practice to adjust the frequency, or, in more popular terms, to "tune" the receiver by employing coils of fixed inductance and to tune the circuit associated with said coils and detecting and amplifying device by means of 40 variable condensers bridged across such coils.

45 In accordance with my present invention I provide an inductance coil for each amplifier electron tube and for the detector tube, but instead of bridging such inductance with but one variable condenser, I do so with a plurality of condensers, all having the same capacity and characteristics, any of which condensers may be thrown out of service by means of a suitable switch. It is contemplated to use but one of 50 these condensers at a time, and each one of them is therefore chosen of such capacity range that all of the desired frequencies, to which the receiving set incorporating my present invention will respond, may be attained by the use of but one of these condensers. However, it will be 55 within the scope of my invention to have con-

densers of varying range, so that one or more may be bridged across the circuit when lower frequencies than may be attainable with only one condenser are to be received. Also any of these condensers may have a definite and fixed 60 capacity.

This arrangement also greatly increases the frequency range of the receiver to which my present invention is applied, as obviously the lowest frequency to which the receiver may be 65 tuned will be that attained when all the condensers are thrown across the inductance coil, and the highest frequency will be that when none of the condensers are thrown across the coil. For practical purposes, and to produce a 70 receiving set having the power to receive electric waves from a long distance, and to produce sufficient power to allow the use of loud-speaking devices, it is usual to employ a number of stages of amplification at high frequencies before the 75 detector stage, such amplification being commonly termed "radio-frequency amplification."

80 Receivers incorporating such radio-frequency amplification usually have two stages of this amplification, followed by a "detector" stage, the signals obtained from the latter stage then being passed either through a telephone instrument or further amplified at lower, or "audio" frequencies to operate the loud-speaking devices already referred to. In accordance with my present invention, no change is made in the audio-frequency parts of the receiving set.

85 A further object of my invention is to provide means whereby a radio receiver may be tuned to a given frequency by one of the condensers 90 that is bridged across the inductance coil by closing a switch, whereupon the said switch may be opened, and a second switch connecting a second condenser may be brought into service, and this second condenser may then be tuned to 95 a frequency different from that of the first condenser; and this may be repeated as many times as there are condensers provided. This makes it possible to tune the receiving set to a plurality of sending stations, any of which may be instantly tuned in by throwing the corresponding switch connecting the condenser that is adjusted to tune in that particular frequency.

105 In sets using a number of tuning units that are cascaded, as for example in sets using two stages of tuned radio-frequency amplification and one tuned detector stage, it has become customary to provide a condenser for each of these stages. Formerly these condensers were independently variable, but the most modern con- 110

struction is to vary the capacity of said condensers simultaneously. This is accomplished by either connecting the rotors of such variable condensers by means of pulleys and belts, or by mounting the rotors all on one shaft. This shaft is usually associated with a tuning dial or tuning drum so that the position of the rotors may be ascertained by inspection of the indicia on said dial or drum.

10 In one exemplification of my present invention, I make use of a plurality of sets of variable condensers, each set, for example, consisting of three variable condensers having their rotors mounted on a common shaft, and each of which individual 15 condensers is electrically connected with a suitable inductance coil. Each of these sets of condensers may be thrown into service by a suitable switch. Provision is also made for locking the individual sets of condensers in the position at 20 which any desired frequency is tuned in at its maximum response, so that accidental displacement of the condenser set by accidental movement of the dial or tuning-drum may be avoided.

In the drawing accompanying the present application there is shown in

25 Figures 1 and 2 a diagram of a standard radio receiver having audion tubes. The audio-frequency amplification associated with the receiver is not shown, but merely indicated, as this forms no part of my present invention.

30 In this drawing, Fig. 1 is a diagram of the circuits employed, showing a plurality of condenser sets bridged across suitable inductance coils, and showing the switches employed for throwing the

35 various condenser sets into the circuit.

Fig. 2 is a top plan view showing one form of switch that may be employed for connecting the condenser sets, when the switch is closed; and

40 Fig. 3 is a similar view showing the switch open; and

Fig. 4 is a detail view of the condenser and dial arrangement.

Referring to Fig. 1, it will be seen that there is provided a radio receiving circuit having an antenna 1 and an antenna tuning coil, or as it is usually termed, a radio-frequency air-core transformer RT₁, comprising a primary coil 2 and a secondary coil 3. The said primary is connected either directly to the ground 5, or through a 45 variable condenser 6 shown in dotted outline. One side of the secondary coil 3 is connected with the grid of the first radio-frequency amplifier electron tube 7, and the other side of the coil to one of the leads of the filament of the said 50 electron tube, as is well understood in this art.

The plate of the first electron tube 7 is connected to the primary 8 of a second radio-frequency RT₂, whose secondary 9 is connected to the grid and filament of a second electron tube 60 10 in the same manner as the connections of electron tube 7. The plate of the second electron tube 10 is connected with the primary 11 of a third radio-frequency transformer RT₃, and the secondary 12 of the said transformer RT₃ is connected to the grid of the detector tube 13, a small capacity "grid" condenser and "grid leak" 65 14 being employed in accordance with the well-known principles of the radio receiver construction art. The plate of the detector tube 14 is connected with the primary of an iron-core audio-transformer AT₁ in the usual fashion, which requires no description, as this is now standard practice, and forms no part of the present invention.

70 The secondaries 3, 9 and 12 are bridged by a

plurality of condensers C₁, C₂, C₃, C₄ and C₅; C_{1a}, C_{2a} etc; and C_{1b}, C_{2b} etc. as shown on the drawing (Fig. 1), and switches S₁, S₂ and S₃ are provided to connect such condensers across the said secondaries. It is to be understood that the condensers C₁, C_{1a} and C_{1b} are on a single shaft and are therefore variable simultaneously. The same is true of condensers C₂, C_{2a} and C_{2b}, and of the other condensers bearing the same series of numbers as C₃, C_{3a} and C_{3b} etc.

80 One side of the said condensers, and preferably the stator side, if rotary condensers are employed, is permanently connected to the filament return side of the said secondaries, and the other, preferably the rotor side, is connected to one terminus of the switches. In order to throw any one set of three condensers into the circuit, a switch having the general form shown in Figs. 2 and 3 may be used, although it is within the scope of my invention to use any other form of convenient switching arrangement.

85 In Figs. 2 and 3 it will be seen that I provide a non-conducting shaft 15 having three conducting knife-blades 16 capable of engaging suitable prongs 17. The shaft 15 is rotatable and may be controlled by a dial or handle 18, and the said shaft may pass through the panel 19. Wires 20 and 21 serve to connect the switch terminals with the secondary coils 3, 9 and 12, as already explained. A set of switches is provided for each 95 set of condensers, five in the present case.

90 The operation of a radio receiver constructed in accordance with my present invention is as follows:

95 Supposing for example that the switch controlling the first set of condensers, C₁, C_{1a} and C_{1b}, is closed, the other switches being open. Upon closing the circuits that supply filament current to the electron tubes, in accordance with standard principles, and as shown diagrammatically in Fig. 1, the receiver may then be tuned to a given frequency corresponding to that of the sending station that is to be tuned in, for example one sending on a frequency of 970 kilocycles, and which will for convenience be designated as Station A. This will correspond to a certain dial setting on the dial or drum associated with the shaft of the rotor of the condenser set then in use, namely condensers C₁, C_{1a} and C_{1b}. When the maximum clarity and volume of signal is tuned in for station A, then a suitable set screw is tightened down against the dial or drum of the said condenser so as to prevent the accidental detuning of the said set of condensers. One method of accomplishing this is shown in Fig. 4, in which the 110 rotors of the condensers C₁, C_{1a} and C_{1b} are shown mounted on a common shaft 22, rigidly connected with a dial 23 passing through a panel 23-a. A suitable bracket 24 mounted on the said panel and bent so as to slightly cover the said dial 23 bears a screw 25 having a milled head 26, and by turning the said screw 25 the dial 23 may be locked into position.

115 If thereupon the switch associated with condenser set C₁, C_{1a} and C_{1b} is opened, and the switch corresponding to condenser set C₂, C_{2a} and C_{2b} is closed, then the said second condenser set may be used to tune the receiver to a further station, say Station B, sending on a frequency, for example, of 670 kilocycles. Thereupon, in turn, 120 this condenser may be thrown out of the circuit by opening its switch, and one of the other condenser sets may be thrown into service and tuned for their particular station.

125 It will be seen that the setting for Station A, 130

on condenser set C_1 , etc., will remain unchanged, and the user of the receiver may return to the setting for Station A merely by throwing in the required switch associated with the said condenser. This makes the operation of a receiver incorporating my present invention very easy, for after the set has been tuned for the stations that are to be received, any one may tune in any of the given stations by the mere throw of a switch. 5 This is particularly valuable when the receiver is to be operated by inexperienced persons, when the tuning may be done by an experienced operator, and the condenser setting thereupon locked. All that the inexperienced user then needs to 10 know is the number of the switch corresponding to the station that is to be tuned in.

Any number of independent condenser circuits may be introduced into the circuit, although only five are shown, as this is purely a matter of convenience. The regular operation of the set is in 20 no way disturbed, as four of the condensers may be permanently set for four different stations, and the fifth one may be used for tuning any desired station, even including those that are permanently tuned in, so that it becomes possible, for 25 example, to employ the time between the numbers of a program that is being received to listen to other stations, and then instantly to return to the regular program without changing the setting 30 of the adjusted condensers. Obviously, the condensers to be set permanently may be of the fixed type, and I am not to be limited to the use of variable condensers throughout, nor to the particular types of variable condensers, as types 35 other than those having rotors and stators may be employed.

Obvious modifications of the arrangement shown are to be understood as being within the scope of my invention.

40 What I claim is:

1. In a radio receiver a plurality of sets of 45 ganged condensers, simultaneously variable by a single control, each set being independently variable, inductances common to all of said sets of condensers, and means for selectively electrically

connecting said sets of condensers with said inductances.

2. In a radio receiver a plurality of sets of ganged condensers simultaneously variable by a single control, each set being independently variable, inductances common to all of said sets of condensers, means for selectively electrically connecting said sets of condensers with said inductances, and means for preventing the accidental variation of the setting of the said sets of condensers. 80

3. In a radio receiving set means for permanently tuning said set to a given number of sending stations without impairing the ability of said set to be tuned to stations other than those to which it is permanently set, which comprises inductance coils, sets of ganged variable condensers each set varied by a single control and being bridge across said coils for tuning said coils to any frequency within the range of the combination of said coils and said sets of condensers, means for connecting and disconnecting the individual sets of ganged condensers to and from said coils, and circuits associated with said coils and condensers for amplifying and detecting electric waves. 90

4. In a radio receiving set, the combination of a number of inductance coils and associated circuits, each of said coils being coupled with an audion, means comprising a number of sets of simultaneously variable ganged condensers associated with said coils, each set being operated by a single control for tuning said coils, and circuit changing devices for introducing any one 105 of the sets of condensers into said circuits. 110

5. In a radio receiving set having a plurality of inductance coils and associated circuits, means for selectively tuning said coils to a series of fixed frequencies, comprising the combination of a plurality of sets of ganged condensers simultaneously variable by a single control, and means for connecting any one of the said sets of condensers into the system as a unit by suitable switching means. 115
